UNITED STATES PATENT OFFICE.

THOMAS J. WATTS, OF BALTIMORE, MARYLAND, ASSIGNOR TO THE TOWNSEND GRACE COMPANY, A CORPORATION OF MARYLAND.

STRAW HAT.

Application filed December 10, 1924. Serial No. 754,893.

To all whom it may concern:

Be it known that I, THOMAS J. WATTS, a citizen of the United States of America, residing in the city of Baltimore, State of Maryland, have invented certain new and useful Improvements in Straw Hats, of which the following is a specification.

A well-known and generally recognized defect incident to all straw hats of the stiff, close-fitting variety as the sailor hats worn by men and boys is the extreme rigidity of the structure, particularly at the base of the side crown where it joins the brim and where with the mere intervention of the sweat-band or leather which has but a slight cushioning effect, it bears directly against the head of the wearer.

The rigidity of the hat at this point results not only in discomfort but in a greater or less degree of actual injury, arresting the circulation in the scalp, interfering with the growth of the hair and causing headache.

This difficulty has to some extent been overcome in the manufacture of silk hats, derbies and felt hats by the use of a softer material connecting the brim and crown of the hat and forming the base of the crown, and the inner portion of the brim where they contact the head, and the improvement of stiff straw hats has been attempted along these lines by the obvious expedient of making the entire fabric at this point of a wholly different straw supposed to be inherently more flexible but which does not by this mere substitution of materials give any appreciable increase of flexibility. This variation in texture has been found objectionable on account of the appearance, particularly in connection with the popular type of sailor hat made of heavy saw-tooth braid the insert of narrow smooth braid is glaringly apparent and not desirable.

The object of this invention is to produce a hat which is flexible at the point named and of almost the same uniform appearance and preferably in the main of the same material as the stiff straw hats, particularly of the saw-tooth pattern, though it may be applied to other hats. The improved hat is extremely flexible as to the portions immediately adjacent and in contact with the head of the wearer, giving the feeling and comfort of the softest felt and the cool-

ness of a straw hat together with the style and appearance of a stiff sailor hat.

The rigidity of the regular type of sailor hat and other stiff straw hats results not so much from the use of a heavy braid as from the application to the hat after sewing of a sizing or stiffening material which enters between the adjacent braids and assists in holding them in position, the assistance of the sizing material being necessary to hold the braids in position on account of the invisible stitch which instead of being passed through and through the hat, merely connects the edges of the braids being passed under the surface but not through the overlying outer edges of the braid. Some hats have been sewed through and through at this point and the sizing partially omitted. All the improvements in the direction named actually result from the omission or partial omission of sizing rather than from variation of fabric. The use of finer straw fully sized does not give any beneficial result. The through and through sewing of the coarse straw and the use of the smooth fine straw braid at this point produce an unsightly hat and one which has only slightly increased flexibility even when the sizing is reduced. It cannot be fully dispensed with, some sizing is necessary to preserve the straw.

The applicant has discovered that a much more flexible construction than either of those heretofore known can be produced by forming a composite braid of saw-toothed and smooth material as sennet and shansi overlapped and sewed together longitudinally. Sennet is a flat wide straw used to make heavy saw-toothed braid of the kind used in the manufacture of men's stiff sailor hats with a rough saw-tooth finish, and shansi is a fine straw used in the manufacture of smooth braid from which smooth straw hats, other than Panama hats, are made. Both of these materials are common stock articles well-known to straw hat manufacturers by these terms. This composite braid is inherently more substantial and stiffer than the full sennet generally used in the manufacture of sailor hats, but the combining in this way of the strips of material which are preferably saw-toothed split sennet and shansi gives a lateral hinging

effect which in the completed structure of the hat results in a remarkable and hitherto unequalled degree of flexibility at the points already mentioned where this material is used for this purpose.

This new material has the advantages over the use of uniform fine straw for this purpose not only of increased flexibility but it presents saw teeth with the same spacing as 10 in the remainder of the hat, giving uniformity of appearance. It may be sewed through and through without making the stitches apparent and it is stronger than the other braids mentioned, so that when sewed 15 through and through practically all the sizing may be omitted without sacrifice of the strength and durability. The resulting flexible straw hat fabric forming the head contacting zone is of full strength, flexible 20 enough to give as great degree of comfort as the softest felt hat, and its appearance so resembles the rest of the saw-tooth structure as to give the desired uniformity.

The hat which is illustrated has the main 25 portion of the crown and brim made of saw-toothed braid with invisible sewing connecting the braids together and the usual stiffening assisting in holding the braids, the base of the crown and the inner edge of 30 the brim being formed of a composite braid, one part of the braid consisting of a smooth weave and the other of a saw-tooth straw corresponding to the saw teeth of the full 35 sennet of which the rest of the hat is made, the double braid structure providing saw-teeth in the flexible portion spaced as in the main structure of the hat and hence producing an appearance of the soft portion of the 40 hat similar to that of the stiff or main structure.

In the accompanying drawing I have illustrated a straw hat embodying the features of my invention in the preferred form.

In the drawing—

45 Figure 1 is a side elevation of the hat.

Figure 2 is a plan of the hat which is fragmentary as to the showing of the fabric.

Figure 3 is a fragmentary vertical section on the line 3, 3 of Figure 2.

50 Figure 4 is a fragmentary elevation corresponding to Figure 3 and looking at the side crown and brim from the right of the same as seen in Figure 3, both figures being full size.

55 Figure 5 is an enlarged plan of the double braid used in the manufacture of the flexible portion of the hat, one member of the braid being broken off short of the other to expose the latter for the purposes of full illustration.

60 Referring to the drawings by numerals, each of which is used to indicate the same or similar parts in the different figures, the hat 1 as illustrated is of the popular type of men's sailor hats, though it may be any kind

of a stiff straw hat. Such hats are ordinarily made throughout of saw-tooth braid 3, the most popular material being full sennet overlapped and sewed with invisible stitches 4. The braid is in a single line extending outward in a spiral from the centre of the top of the crown and down the sides.

The important feature of the invention resides in the provision of a flexible area at the portion or contact zone of the hat referred to, which has the desired property of flexibility to a greater degree than hitherto attained in this connection and is of similar appearance to the remainder of the hat structure and of equal strength and durability. To this end I make the straw fabric at this point of a composite braid consisting of strands or strips of different straws preferably comprising a straw 5 as sennet like the remainder of the hat and other preferably smooth spacing material 6 as shansi connected together to form a single braid. The combining of the two kinds of braid in this way gives a full sized braid of sufficient strength to be used without adhesive when sewed through and through, and the combination of the two straws provides for the presentation of edges and surfaces like the full sennet or principal material and gives a spacing of the rough edges corresponding to the rest of the hat enhancing the effect of uniformity.

In accordance with my invention I provide a composite straw braid 7 consisting of a strand or strip of saw-tooth sennet 5 or other distinctive material like the rest of the hat and a strand or strip of fine straw as shansi 6, the one overlying the other, the two being overlapped to give the desired width of braid equal to that in the rest of the hat and stitched through and through with a line of stitching 8 which holds the thicknesses of strips 5 and 6 in the relation in which they appear in Figure 5 or otherwise secured, forming a braid which when sewed into the hat structure at the inner portion of the rim and the base of the side crown as previously described, the neighboring lines of braid of this type being lapped one over the other and sewed together by through and through stitches 9 forms a flexible straw fabric of sufficient strength to resist the stresses to which it is subject in use without the necessity for strengthening the fabric by means of glue or other adhesive which appears in the capacity of a stiffening and strengthening material in other straw hats and in the remainder of the structure of the hat which is the subject of the invention.

While I have described the new form of braid as composed of braided shansi and split sennet, it may of course within the scope of the invention be constructed of other straws or materials having identical

or desired properties, the important result obtained by the invention being the construction of the zone of the hat immediately in contact with the head of a type of braid which may be sewed through and through, giving the necessary strength without the use of glue or other stiffening and adhesive material, attaining the highest degree of flexibility, giving uniform appearance of an ordinary stiff hat, and also concealing and disguising the through and through sewing.

The hat which is the subject of the invention is more comfortable due to the greatly increased flexibility of the head contacting portion, and of more pleasing appearance, due to the uniform spacing of the saw-teeth, than any hat of this general type previously offered.

I have thus described specifically and in detail a single embodiment of my invention in order that the nature and manner of constructing the same may be clearly understood; however, the specific terms herein are used descriptively rather than in a limiting sense, the scope of the invention being defined in the claims.

What I claim and desire to secure by Letters Patent is:

1. A braid for the flexible portion of men's sailor hats and the like, the same consisting of a strip of a fine smooth braided straw and a strip of coarser braided straw of roughened distinctive outline, the two being placed parallel, one partially overlying the other, and a through and through longitudinal seam connecting the two together, forming a braid of standard width having one roughened edge and one smooth edge portion.

2. A straw braid for straw hats composed of relatively coarse straw braided to give a saw-toothed effect and a braided strip of relatively fine straw, one overlying the other, the composite braid presenting one saw-toothed edge and one smooth edge.

3. A straw hat having the main portion of the crown and brim made of saw-toothed sennet braid stiffened and secured by means of a stiffening and adhesive material and a flexible portion containing less adhesive than the main portion, the flexible portion connecting the brim and crown, and consisting of saw-toothed sennet and shansi laid alternately and overlapped so that the saw teeth are spaced apart a distance substantially equal to the spacing of the saw teeth in the main structure, and longitudinal seams extending through and through the shansi and split sennet where they overlap and hold the hat structure together.

4. A straw hat having the main portions of the brim and crown composed of rough braid stiffened by means of an adhesive material, stitching holding the braids in posi-

tion, and a flexible head contacting portion connecting the brim and crown composed of a rough straw and a smooth fine straw laid alternately and overlapped and stitching holding them together so that the rough portions are substantially equally spaced, the flexible portion containing less sizing material than the main portion of the hat structure.

5. A straw hat having the main portions of the crown and brim made of a rough straw braid, invisible stitching holding the braids in the constructed relation, a stiffening adhesive also assisting in holding the braids and a flexible head-contacting portion at the base of the crown and the inner edge of the brim, the same consisting of a composite braid of the full width of the rough braid comprising a strand of smooth fine straw and a strand of rough material, and a seam fastening them together, the braid being overlapped, and stitching sewing the overlapped portions together whereby the edges of the rough braid in the flexible portion are spaced substantially equally to the spacing of the edges of the rough braid in the main portion, the flexible portion containing less stiffening and adhesive than the main portion of the hat.

6. A straw hat having the main portions of the brim and crown composed of rough braid stiffened by means of an adhesive material, invisible stitching holding the braids in position, and a flexible head-contacting portion connecting the brim and crown composed of a rough straw and a smooth fine straw laid alternately and overlapped and stitching holding them together so that the rough portions are substantially equally spaced, the sewing extending through and through the overlap, the flexible portion containing less sizing material than the main portion of the hat structure.

7. The method of making a straw hat having a stiff brim and crown, and a flexible head-contacting portion which consists in forming the brim and crown of braid which is overlapped and sewed together at the overlapped portion and securing the same by means of a sizing and stiffening adhesive material and forming a composite braid by overlapping strips of straw fabric laterally and sewing them together, constructing the lower portion of the brim and the inner portion of the crown of the composite braid, and sizing the composite portion to a less degree than the remainder of the hat.

Signed by me at Baltimore, Maryland, this 8th day of December, 1924.
